3 Claims. (Cl. 160—173)

The present invention relates to a slat lifting mechanism for a Venetian blind of the type wherein a plurality of blind slats are suspended from a head box in the shape of a ladder by means of suspender tapes and raised or lowered by means of lifter tapes.

The conventional Venetian blind of this type employs two or more lifter tapes, each of which is passed through the vertically aligned openings in the blind slats and is fixed at the upper end thereof onto a lifter drum mounted on a lifter shaft in the head box and at the lower end thereof to a bottom plate. The blind slats can be raised by rotating the lifter shaft in one direction so as to wind up the lifter tapes onto the respective lifter drums to raise the bottom plate, and the slats can be lowered by rotating the lifter shaft in the other direction so as to unwind the lifter tapes from the respective lifter drums to lower the bottom plate.

In such a conventional Venetian blind, the rotation of the lifter shaft in the slat lowering operation must be stopped just when the slats have been fully lowered, that is, the lifter tapes have been completely unwound from the lifter drums, and if the rotation is inadvertently continued after the tapes have been fully unwound the tapes will be wound up onto the lifter drums in the direction opposite to the normal winding up direction, which may damage or break the lifter tapes.

Also, the rotation of the lifter shaft in the slat lowering operation must be stopped if the bottom plate comes into contact with some obstacle which prevents the bottom plate from further lowering. The continued rotation of the lifter shaft will unwind the lifter tapes notwithstanding the slats being not able to move downward, thus resulting in the damages of the lifter tapes and blind slats.

It is an object of the present invention to avoid the above-mentioned difficulties in the conventional slat lifting mechanism for the Venetian blind.

In accordance with the present invention the slat lifting mechanism for the Venetian blind is provided wherein the lifter tape is not directly fixed to the lifter drum but is connected thereto through the intermediary of friction means which is in tight frictional engagement with the lifter drum so long as the weight of the bottom plate is imposed on the lifter tape but in loose frictional engagement when the weight of the bottom plate is not imposed. The friction means may be made of a spring having a drum engaging portion or portions encircling the lifter drum and a tape fixing portion to which the upper end of the lifter tape is fixedly connected.

In order that the invention will be more fully understood and readily carried into effect, the following detailed description is given with reference to the accompanying drawings in which:

FIGURE 1 is a front elevation of a slat lifting mechanism according to the present invention; and

FIGURE 2 is a perspective view of a spring employed in the slat lifting mechanism as shown in FIGURE 1.

Referring to the drawings, the slat lifting mechanism according to the present invention comprises a lifter drum 2 having a tape winding groove 1 and mounted on a lifter shaft 4, the drum 2 and the shaft 4 being housed in a

2

head box (not shown) as in the conventional construction of the Venetian blind. Usually two or more lifter drums 2 are mounted on the lifter shaft 4 to raise the bottom plate at two or more spaced points of the slats.

A spring 5, which is shown clearly in FIGURE 2, encircles the groove 1 of the lifter drum 2. The spring as shown in the drawings has two helically wound portions at the both ends thereof, which are not fixed but wound around the groove 1 in the direction corresponding to that of the slat raising rotation of the lifter shaft, and a tape fixing portion 3 at its central part to which the upper end of a lifter tape 6 is fixed. Alternatively the spring may have only one helically wound portion at one end and the tape fixing portion at the other end.

Normally the weight of the bottom plate (not shown) applied to the lower end of the lifter tape 6 acts to tighten the helically wound portion of the spring 5 into tight frictional engagement with the peripheral surface of the tape winding groove 1 of the lifter drum.

When the lifter shaft 4 is rotated in the slat raising direction, the spring 5 is more firmly tightened on the periphery of the groove 1 since the spring 5 is wound around the groove 1 in the direction corresponding to that of the slat raising rotation of the lifter shaft 4, so that the spring is rotated with the lifter drum and thus the lifter tape 6 is wound up onto the drum to raise the blind slats.

When the lifter shaft 4 is rotated in the opposite direction, namely, slat lowering direction, the spring 5 is rotated with the lifter drum and the lifter tape 6 is unwound from the drum to lower the blind slats. Thus the raising or lowering of the blind slats can be accomplished by the rotation of the lifter shaft 4 in one or other direction.

When the slat is completely lowered, that is, the bottom plate reaches to the lowest position, the weight of the bottom plate becomes supported entirely by suspender tapes (not shown) and the weight load is relieved from the lower end of the lifter tape. The spring is loosened into loose frictional engagement with the peripheral surface of the groove 1, so that the rotation of the drum is not transmitted to the spring, which is held stationary even if the rotation of the lifter shaft is continued.

Also, if the bottom plate comes into contact with some obstacle on the way of the lowering path, the load is relieved from the lower end of the lifter tape, so that the rotation of the lifter drum is no longer transmitted to the lifter tape.

It will be understood from the above explanation that in accordance with the present invention the unwinding of the lifter tape is automatically stopped when the slats are fully lowered or when the bottom plate comes into contact with some obstacle which prevents it from further lowering, even if the rotation of the lifter shaft is continued.

Although a specific embodiment of the present invention has been described, it should not be construed as limited thereby but to include various other equivalent features as set forth in the claims appended hereto.

It is understood that any suitable changes, modifications and variations may be made without departing from the spirit of the invention.

60 What is claimed is:

1. In a slat lifting mechanism for a Venetian blind, the improvement comprising a lifter shaft, a lifter drum mounted on said shaft, a blind slat lifting tape adapted to be wound up onto the lifter drum, and frictional means which is fixed to the upper end of the lifter tape and frictionally engages with the lifter drum by a load applied to the lifter tape.
- 65 2. In a slat lifting mechanism for a Venetian blind, the

improvement comprising a lifter shaft, a lifter drum mounted on said shaft, a blind slat lifting tape adapted to be wound up onto the lifter drum, and spring means fixedly connected to the upper end of said tape and having a portion frictionally engaging the lifter drum.

3. In a slat lifting mechanism for a Venetian blind, the improvement comprising a lifter shaft, a lifter drum mounted on said shaft, a blind slat lifting tape adapted to be wound up onto the lifter drum, and a spring having a portion fixedly connected to the upper end of said lifting tape and at least one helical portion wound around said lifter drum.
